UNITED STATES PATENT OFFICE.

ARTHUR P. YOUNG, OF KENILWORTH, AND JOSEPH HUTT, OF COVENTRY, ENGLAND,
ASSIGNORS TO GENERAL ELECTRIC COMPANY, A CORPORATION OF NEW YORK.

TELEPHONE RECEIVER.

Application filed May 28, 1926, Serial No. 112,362, and in Great Britain June 10, 1925.

The invention relates to electromagnetic instruments of the kind having a permanent magnet with pole pieces attached to its ends, and particularly to telephone 5 receivers or transmitters for use in connection with wireless or ordinary telephony or telegraphy.

In the patent of Arthur P. Young, No. 1,628,383, granted May 10, 1927, and entitled "Telephone receivers", there is described a telephone receiver, or the like, having a pole piece of magnetic material which has been shaped to fit closely around the end of the permanent magnet on two opposite sides thereof, and then pressed so as to make a firm connection therewith. The present invention relates to improvements and modifications of the invention set forth in the aforesaid 10 pending application and is applicable to loud speakers and apparatus for picking up sounds, as well as to the ordinary telephone receiver.

According to the present invention the 15 pole pieces are made of slightly greater width than the permanent magnet or otherwise arranged so that when they are pressed on to the permanent magnet the metal of the pole pieces flows over the edges of the permanent magnet, the former being softer than the latter, with the result that the permanent magnet is to some extent embedded in the metal of the pole pieces, and the pole pieces are accurately positioned with respect to the magnet and are prevented from 20 moving laterally with respect to the magnet. In instruments of this character, in which the greater part of the magnetic system is embedded in composite insulating 25 material, the latter holds the pole pieces in their correct relative positions. Our present improvement enables the same magnetic system to be mounted in a casing by means other than molding in composite insulating material.

A further feature of our invention consists in providing one or both of the pole pieces with lugs. For instance, each pole piece may have one or two lugs or lateral 30 projections below the magnet by means of which the magnet assembly is secured to the casing by rivets, screws, or the like. Similarly one or more lugs or lateral projections may be provided on one or both pole 35 pieces above the magnet for the purpose of

attaching a terminal board in the casing below the coils on which the connections between the coils and telephone leads may be made.

The novel features which we believe to be characteristic of our invention are set forth with particularity in the appended claims. Our invention itself, however, will best be understood from reference to the following specification taken in connection with the accompanying drawing in which Fig. 1 is a top plan view of a telephone receiver embodying the features of our invention with the diaphragm and cover removed; Fig. 2 is a sectional view taken on the line 2-2 of Fig. 1; Fig. 3 is a transverse sectional view of Fig. 2; Fig. 4 is a top plan view of a telephone receiver showing a modification of the invention, the diaphragm and cover being removed; and Fig. 5 is a sectional elevation thereof about the line 5-5. Like reference numerals are used throughout the drawings to designate similar parts.

With reference to the drawings the magnetic circuit includes query-shaped pole pieces 11 arranged with their curved portions 12 surrounding the ends of a permanent bar magnet 13 and their straight portions 14 adjacent to one another and on the same side of the magnet. The limbs 14 are spaced above the magnet as at 15 and provided with flat portions 16 which act as seats for the operating coils 17. The width of the pole pieces 11 may be slightly greater than the width of the permanent bar magnet 13 so that when the pole pieces are pressed on to the ends of the bar magnet the edges of the pole pieces slightly overlie the edges of the magnet, thus forming a pocket and preventing the lateral displacement of the magnet with respect to the pole pieces. When the pole pieces are made of metal that is softer than that of the magnets, as is usual, then the width of the pole pieces may in the first place be the same as that of the magnet and, if the pressure applied to the pole pieces when they are in position around the magnet ends is sufficient, the metal of the pole pieces will flow slightly in lateral directions over the edges of the magnet, thus again firmly embedding the ends of the magnet in the pole pieces.

The pole pieces are here shown as provided with lugs 18 extending laterally from

their bases, by which lugs the magnet assembly can be screwed into or riveted to the instrument casing 19. Upper lugs 21 may be formed integrally with the upper portion 5 of the pole pieces, these lugs serving the purpose of carrying a terminal board 22 of insulating material upon which the terminals 23 for the cord 24 are mounted.

In order to cheapen the construction still 10 further we may provide only two lugs for fixing the magnet assembly to the casing, say, one lug formed integrally with each pole piece and extending on opposite sides of the magnet; and another lug higher upon 15 each pole piece and extending opposite the other lug thereof, for the attachment of the terminal board. This latter arrangement facilitates the use of rivets for securing the magnet assembly to the casing.

20 In the arrangement shown in Figs. 4 and 5 the magnet assembly is secured by means of a bent strip 25 passing over the magnet at 26 and riveted to the casing at 27. One end of the strip 25 is brought up at 28 to 25 anchor the terminal board 22 and the other end of the strip is arranged to anchor the two leads of the cord as shown at 29. With

this arrangement, it will be noticed, no lugs are formed on the pole pieces.

What we claim as new and desire to secure 30 by Letters Patent of the United States, is:—

1. A telephone receiver or like device comprising a permanent magnet, and a member bent around said magnet to form opposed pole pieces.

2. A telephone receiver or like device comprising a permanent magnet, and a member arranged to surround the ends of said magnet and to form opposed pole pieces.

3. A telephone receiver or like device comprising a casing and a permanent magnet, a pole piece embracing one end of said magnet, said pole piece comprising two parallel portions, each of said parallel portions being provided with a projecting lug, one of 40 said lugs being adapted to secure said magnet and pole piece in position in the casing and the other of said lugs being adapted to support a terminal board.

In witness whereof, we have hereunto set 50 our hand this 29th day of April, 1926.

ARTHUR P. YOUNG
JOSEPH HUTT.
